UNITED STATES PATENT OFFICE.

WILLIAM C. HUGULEY, OF BELLEVILLE, NEW JERSEY, ASSIGNOR TO M. S. MORK & COMPANY, OF NEWARK, NEW JERSEY, A CORPORATION OF NEW JERSEY.

WRAPPING MACHINE.

Application filed March 11, 1925. Serial No. 14,677.

To all whom it may concern:

Be it known that I, WILLIAM C. HUGULEY, a citizen of the United States, and a resident of Belleville, county of Essex, State of New Jersey, have invented certain new and useful Improvements in Wrapping Machines, of which the following is a specification.

This invention relates to a wrapping machine and to mechanisms for performing wrapping and similar operations. The invention also relates to improvements in an apparatus for operating mechanisms from individual motive sources under a central or unitary control to carry an article through a process of manufacture.

Mechanisms for performing operations or successions of operations such as those required in wrapping a wrapper about an article and securing it have been heretofore driven from a single motive power source through shafts, gears, cams and similar transmitting elements to provide the proper succession of movements. Where the mechanisms are to be operated simultaneously or in rapid succession and are variously distributed throughout a machine, and particularly if there are several mechanisms requiring movements in different directions with definite time intervals, a complicated transmission mechanism is required to drive the mechanisms from the central power source and to provide the various changes of movement and of speed required for this purpose. This extensive transmission mechanism not only adds greatly to the complexity of the machine, consumes power, and affords liabilities for the mechanism to get out of order, but also imposes limitations on the flexibility and effectiveness of the mechanism as for example when instantaneous movements are required at definite time intervals. This is particularly the case in mechanisms such as are required in machines for wrapping articles, in which case a large number of successive operations must be performed in order to position the wrapper and article to be wrapped in their proper relative positions and to carry through a large number of difficult folding operations in different directions. It is therefore

highly desirable in mechanisms of this type to have the various elements move with speed and precision.

An object of my present invention is to provide an apparatus of simple construction 55 for performing various separate but inter-related movements, such as those required for wrapping articles.

Another object of the invention is to provide a wrapping machine for rapidly, neatly and accurately wrapping articles of irregular shapes and of varying dimensions.

A further object of the invention is to provide a method and apparatus for controlling and timing a number of separate 65 mechanisms and individual driving means to perform a number of operations on an article and to enable certain operations to be performed instantly at sharply defined time intervals.

Other objects of the invention are to provide a wrapping machine in which the various mechanisms for advancing and positioning an article and wrapper and to form the various folds are pneumatically operated 75 under the control of a unitary timing and control means, to provide a means for advancing an article to successive distances under the action of separately acting means under unitary control, to provide pneumatically operating means for positioning and advancing an article and for wrapping a wrapper about said article, to an improved means for supporting an article permitting a wrapper to be tucked beneath its bottom 80 surface, to provide a motive source for handling articles which provide a yielding, resilient movement, and to provide a mechanism by which such movement may be transformed into a positive support for other 85 movements, to provide an improved control means for the separately driven mechanisms, to provide an improved and simplified supporting and suction transmitting means and to provide a resilient centering, pressing and holding means for articles passing through a series of wrapping or similar operations.

With these and other objects in view, which will appear in connection with the following description, the invention com- 100

prises the method and apparatus described and set forth in the following specification and claims.

The various features of the invention are 5 illustrated in the accompanying drawings in which:

Fig. 22 is a view similar to that of Fig. 21 showing a further position of the mechanism,

Fig. 23 is a view similar to that of Fig. 21 showing the mechanism in position making 85 a further fold in the wrapper enveloping the article to be wrapped,

Fig. 24 is a vertical sectional view through the wrapping mechanism taken on line 24—24 of Fig. 23,

Fig. 25 is a vertical sectional view on a plane taken similar to that of Fig. 24 showing the mechanism in a further folding position,

Fig. 26 is a view of the mechanism of Fig. 25 taken on line 26—26 of Fig. 25,

Fig. 27 is a plan view of a portion of the wrapping mechanism,

Fig. 28 is a view similar to that of Fig. 27 with the mechanism in a further position of movement,

Fig. 29 is a detail view in plan of a portion of the mechanism of Figs. 27 and 28 showing different stages of its movement,

Fig. 30 is a vertical sectional view of a 105 portion of the wrapping mechanism for further folding operations taken on the plane of Fig. 25,

Fig. 31 is a sectional view taken on line 31—31 of Fig. 30,

Fig. 32 is a view similar to that of Fig. 30 showing the mechanism in a further position of movement,

Fig. 33 is a view of a portion of the machine taken on line 33—33 of Fig. 32,

Fig. 34 is a view taken similar to that of Fig. 32 showing the manner of displacing a wrapped article from the wrapping mechanism and feeding it to an outlet feedway,

Fig. 35 is a view of an outlet feedway of 120 the machine,

Fig. 36 is a view showing the relative positions of a wrapper and an article when in position for the wrapping operations,

Figs. 37 to 42 inclusive are views showing the article and wrapper in various stages of the wrapping operations,

Fig. 43 is a view of the completely wrapped article,

Fig. 44 is a perspective view of a combined 130

frame and suction transmitting system embodying a preferred form of these features and

5 Fig. 45 is a vertical sectional view of a modified form of control cam shaft construction embodying a preferred form of the control means.

10 In my present invention, the article under treatment is operated on by a series of mechanisms having individual motive powers under the control of a central or unitary control and timing means, the mechanisms operating to advance the article through the various operations, some of the mechanisms

15 acting in succession and others simultaneously or in groups. In the preferred embodiment of the invention, the individual motive powers are in the form of pneumatically operated bellows having a movable wall driv-

20 ing the respective mechanisms and moving when connected at the proper times to a common source of suction. The suction connections are made through individual control means which are controlled through pneu-

25 matically operated mechanism from a central cam shaft or other suitable timing device whereby the bellows are connected to and disconnected from the source of suction at the proper time intervals. Through

30 the action of these mechanisms, as applied to the wrapping of an article, the articles are taken singly from a feeding slide or chute and placed on a feedway in which they are fed singly to a plunger and accurately centered thereon. A wrapper is then

35 taken from a supply stack and placed in proper position above the article, being held in position at its edges by suction. The plunger is then lifted, carrying the article 40 upwardly through the plane of the wrapper, carrying the central portion of the wrapper upwardly with it and causing the side portions of the wrapper to be drawn snugly downwardly against the sides of the article.

45 The article is then supported at its side edges through the wrapper and the portions of the wrapper depending downwardly from the supported edges are tucked inwardly beneath the article. The portions of the wrap-

50 per projecting past the ends of the article are then tucked upwardly from the bottom and sidewise against the end of the wrapper leaving only an upper projecting portion

55 projecting past the ends of the article. To fold these projecting end portions downwardly against the ends of the article, the supporting surface of the lifting plunger is raised to lift the partly wrapped article upwardly between a pair of guiding and press-

60 ing plates which press the projecting portions downwardly against the ends of the article. The article is then supported at its lower end edges and the portions of the wrapper extending downwardly from these edges are then tucked beneath the bottom

end portions of the wrapper by means of endwise sliding tucker plates. The article thus completely wrapped, is then pushed upwardly by a succeeding article and carried sidewise onto an outlet guideway. As 70 the action of the suction on the bellows is instantaneous, and can be accurately timed the various operations are carried out with great speed and precision and where necessary can be cushioned to obtain any desired 75 effect. As no transmission means to the bellows is required except for the suction and control tubes a maximum of freedom in the placing of the mechanisms is provided.

Referring more particularly to the accompanying drawings, the invention is illustrated as applied to the wrapping of pieces of candy 50, which in the particular case illustrated, are flat on only one face and may vary in dimensions within limits. A supply 80 of these pieces are placed on a loading tray or platform 51 by the operator and fed sidewise onto an inclined slide or chute 52, each piece sliding downwardly toward the bottom of the slide. The lowermost piece is retained 85 on the slide by means of a depending finger 53, Figs. 4 and 14, extending into the slide from an end of a lever 54 pivoted at 55 on the top of the slide, and the succeeding pieces are retained by the preceding pieces and 90 form a continuous succession of contacting pieces to the top of the slide.

The lever 54 is normally held with its forward end tilted downwardly and with the finger 53 projecting into the slide 52, by 100 means of a spring 56 stretched between a pin 57 projecting upwardly from the lever and a stationary pin 58 projecting upwardly from the slide 52, but may be tilted against the action of the spring 56 to lift the finger 105 53 and permit the lowermost piece 50 to slide downwardly into a loading trackway 59 leading to the wrapping mechanism. When the lever 54 is tilted to release the lowermost piece 50, the next succeeding piece 110 is retained in position by means of a lever, 60, pivoted at 61 on the top of the slide, which is tilted downwardly to intercept the next succeeding piece when the finger 54 is lifted and is held down until the lever 54 115 and finger 53 have returned to their holding positions.

The tilting of the levers 54 and 60 to accomplish the advancement of the pieces singly at the proper intervals is actuated by 120 a pneumatically actuated motive device controlled pneumatically from a central control mechanism which controls the various positioning and folding mechanisms of the wrapping mechanism to actuate these mechanisms 125 in their proper timed sequence. This pneumatic motive device may be of any suitable construction but in the preferred embodiment comprises a bellows 62 having an upper wall 63 fixed to and supported by a suction 130

and control box 64, Fig. 4, supported by standards 65 extending upwardly from the slide 52. The bellows also comprises a lower plate 66 having a hinged connection with the upper plate 63 at its forward end and an enclosing flexible fabric side wall 67. The bellows 62 is normally held in open position by means of a spring 68 between the upper and lower plates 63 and 66 but when the levers 54 and 60 are to be tilted, communication is opened between the interior of the bellows and the suction box 64 causing the side walls 67 to fold inwardly and drawing the lower plate 66 upwardly against the action of the spring 68 and causing it to tilt about its forward axis.

The movement of the lower plate 66 is transmitted to the levers 54 and 60 through an arm 69 projecting forwardly from the lower plate 66 and having a downwardly depending finger 70, Fig. 14, terminating a short distance above the lever 54. As the bellows 62 collapses under the application of suction and tilts the plate 66 and arm 69, the downward movement of the arm 69 is transmitted to depress the lever 60 through a rod 71 connecting the arm to the lever. To provide a resilient pressure of the lever 60 on the piece of candy 50 and thus prevent crushing the piece, the pressure of the arm 69 is transmitted through a spring 72 encircling the rod 71 and confined between an upper nut or collar 73 bearing against the lower face of the arm 69 and a lower nut or collar 74 bearing against the upper face of the lever 60. The rod 71 is threaded to the lever 60 and has a head 75 resting on the upper surface of the arm 69 by which the rod and lever may be returned to their upper positions when the bellows returns to its normal position.

When the arm 69 is tilted downwardly, it first depresses the lever 60 through the spring 72 until the piece next to the lowest piece 50 is engaged and thereafter the depending finger 70 contacts with and depresses a rearwardly projecting arm 76 of the lever 54 and lifts the lever to release the lowermost piece of candy. As the bellows 62 is re-inflated, the lever 54 first returns to its holding position and the lever 60 is then lifted to permit the piece retained thereby to slide downwardly until stopped by the finger 53.

The suction and control box 64 may be of any suitable construction, such as that shown by way of example in Fig. 4 of the drawings. In this type of control box, the interior of the bellows 62 may be connected through a passage 77 either to the atmosphere, through an opening 78 controlled by a valve 79 or, to a source of suction through an opening 80, controlled by a valve 81 mounted on a stem 82 common to the valve 79, to a suction chamber 83 which is, in turn,

connected through a passage 84 and tube 85 to a common suction box 86 shown in Figs. 1 and 2. The valve 81 is normally held closed against its valve seat 87 by the pressure of the atmosphere, the valve 79 being then in open position and the valve stem 82 extending through a guide 88 to a plate 89 resting against the surface of a flexible diaphragm 90 forming one wall of the chamber 83. The diaphragm 90 also forms a dividing wall between the suction chamber 83 and a control chamber 91, which is normally in communication with the chamber 83 through a constricted passage 92, thus equalizing the pressures between the chambers. When the bellows 62 is to be operated, air under atmospheric pressure is admitted to the control chamber 91 through a pipe 93 at a greater rate than it can be withdrawn through the passage 92 and serves to press the diaphragm 90 against the valve rod 82 and to thus move the valve 81 to open position and close the valve 79.

The admission of atmospheric air to and through the pipe 93 is controlled by a valve plate 94 at the open end of the tube, Fig. 6, which is normally pressed by means of a leaf spring 95 against the open end of a passageway 96 to which the end of the tube or pipe 93 is connected. To admit air to the tube 93 to actuate the control box 64 and apply suction to the bellows 62, the leaf spring 95 is lifted by means of a cam 97 from which suitable motion is transmitted through a cam roller 98 depending from a lever 99, which is pivoted at 100 at one end and from the other end of which the lifting movement of the cam 97 is transmitted through a sliding rod 101 projecting through a guide 102 to the lower, free, end of the leaf spring 95. The cam 97 is mounted on a cam shaft 103 on which are also mounted other cams for controlling the various mechanisms of the wrapping apparatus in their properly timed sequence. The cam shaft 110 103 may be of any suitable construction but is preferably a plain cylindrical shaft on which the controlling cams 97 may be formed by means of rings 104 secured to the shaft by means of set screws 105 and having side-wise projections 106 in the path of the cam roller 98 and thus forming the cam surfaces. With this construction, the cam may be readily adjusted to obtain any desired timing of the mechanisms.

When a piece of candy 50 is released from the finger 53 it normally slides downwardly onto the feedway 59 leading at right angles from the slide 52 into the wrapping mechanism. To insure against a piece sticking at the juncture of the slide and feed way, and therefore not reaching a position to be pushed into the wrapping mechanism, a forked plunger 107 is provided to slide through grooves 108 in the bottom portion

- of the slide 52 to a position to push the piece 50 onto the feed way 59. For this purpose the plunger 107 is given a forward movement at the proper time by means of a pneumatically actuated bellows 109 and control and suction box 110, Figs. 4 and 14, of a construction similar to that of the bellows 62, from which movement is transmitted to the plunger through a link 111 connected 5 at one end to the moving plate of the bellows 109 and at its other end to a push rod 111^a projecting rearwardly from the plunger 107 through a guide 112. Suction is applied to the box 110 through a tube 113 10 leading to the common suction box 86 and the air for controlling the actuation of the bellows is admitted through a tube 114 the end of which is under the control of the cam shaft 103.
- When the piece or article 50 has been deposited on the feedway 59 it is pushed lengthwise of the feed way, and transversely of the slide 52, by means of a notched pusher 115, Figs. 5 and 15, which is driven through 15 a suitable transmission mechanism from an actuating bellows 116 similar to the bellows 62 and similarly under the control of the cam shaft 103. The movement of the moving plate 117 of the bellows 116 is, for this 20 purpose, transmitted through a link 118 to a lever 119 pivoted at 120 at its lower end and connected at its upper end through a link 121, to the pusher 115, the link 121 being for convenience positioned in recess 122 in the 25 pusher. The pusher is normally drawn to a receiving or non-operating position by means of a spring 123 stretched between the lever 119 and a fixed bracket 124 of the machine.
- Through the movement of the pusher 115, the article 50 is pushed along the feedway 59 until it rests on a plunger plate 125 in approximate position for the wrapping operations. The piece is retained in position 30 on the plate 125 by frictional contact with a pair of brushes 126 and 127 on opposite sides of the plate between which the piece is received and which afford sufficient yielding frictional contact to restrain movement 35 of the article. The article 50 may, however, be accurately centered on the plunger plate, particularly when pieces of non-uniform dimensions are being wrapped. It might for example be left in the position indicated in 40 Fig. 15. If the wrapping mechanism were started with the article in this position, the wrapper would not be positioned on the finished product to bring the printed matter into the desired position or the article might 45 be broken and become jammed in the machine.
- To obtain an accurate and reliable centering of the piece, therefore, a pair of arms 128 and 129, Figs. 5, 7, 15 and 16, are pivoted on 50 vertical pintles 130 and 131 slightly spaced from the rear end corners of the plunger plate 125 and are swung uniformly and simultaneously inwardly over the plunger plate immediately after the piece 50 has been pushed onto the plunger plate thereby centering the piece equidistantly from each end edge of the plunger. The arms are then withdrawn to permit a wrapper to be placed on and wrapped about the piece. For this purpose the proper movement is given to the 55 arms 128 and 129 from a common driving bellows 132 and control box 133, Figs. 1, 3 and 6, mounted beneath a beam 134 of the frame of the apparatus and having a movable wall 135. The movement of the wall 135 is transmitted uniformly and simultaneously to the swinging arms 128 and 129. In this transmission, the movement of the lower plate 135 of the bellows 132 is transmitted 60 through a lever arm 136 secured on the plate 135 through a link 137 to an arm 138 of a bell crank lever 139 journaled on a bracket 140 depending from the beam 134. The movement of the bell crank lever 139 is transmitted from an upright arm 141 of the bell 65 crank lever, through a link 142 to an ear depending from a slide 143, Figs. 6 and 7, mounted to slide forwardly and rearwardly in a guide 144 in alignment with the center of the plunger plate 125. The forward and 70 rearward movement of the slide 143 is transmitted equally to a pair of links 145 and 146, Figs. 6 and 7, pivotally secured at their rear ends to an ear 147 on the slide 143 and at their forward ends pivotally secured to arms 148 and 149 projecting respectively from the plates 128 and 129. Accordingly, when suction is applied to the bellows 132 and the plate 135 lifted, the arms 136 and 138 are swung downwardly, the arm 141, 75 link 142 and slide 143 are moved forwardly and the arms 145 and 146 given a longitudinal forward movement to swing the arms 128 and 129 equally and simultaneously inwardly until they are stopped by the length 80 of the article 50 between and contacting with the inner faces of both arms, the pneumatic pressure of the bellows 132 being insufficient to crush the article. The suction is then 85 immediately released from the control and suction box 133 and the plate 135 pulled downwardly by means of a weight 150 secured to the lower plate 135 or by other suitable means. To enable the arms 128 and 129 to 90 swing freely without interfering with the movement of the pusher 115, the end of the pusher is notched as at 151 to provide room for the swinging arm 138. The control box 133 is connected to the suction box 86 and to a control tube controlled by the cam shaft 103 in a manner similar to that of the control box 64 of bellows 62.
- The piece 50 has now been positioned on the plunger plate 125 in position to receive 95 a wrapper for enclosing it.

The wrappers for enclosing the article 50 are mounted in a stack 152, Figs. 2, 6, 7 and 8, on a platform 153 at the front end of the machine with the printed outer surface up-
5 permost. The platform 153 is guided at each end by a pair of vertical guides 154 and 155 and is pulled upwardly by a pair of springs 156 and 157, Fig. 2, secured by means of straps 158 and frames 159.

10 The platform 153 is pulled upwardly by means of the springs 156 and 157 until the end edges of the uppermost wrapper of the stacks are stopped by contact with the under surfaces of a pair of retaining lips 160 and

15 161 which hold the top wrapper securely in place while affording a central space 162 through which the top wrapper may be drawn upwardly without disturbing the lower wrappers, the lips 160 and 161 serving

20 to hold the lower wrappers in place while the top wrapper is being thus withdrawn.

While the article 50 is being placed and centered on the plunger plate 125, or immediately thereafter, the top wrapper of the 25 stack 152 is lifted directly upwardly then carried rearwardly and deposited with the printed face uppermost immediately above the article 50. In lifting and carrying the wrapper into position, a flat suction box 163, Figs. 2 and 8 having a perforated bottom wall 164 is brought immediately over the space 162 and then lowered until the wall 164 rests on the top wrapper 165 of the stack 152.

30 The interior of the box 163 is connected through openings 166 in a supporting frame 167 to the interior of hollow arms 168 of the frame 167 and from the arms 168 through a hollow supporting tube or rod 169 and a flexible tube 170, Fig. 1, to a suction control box 171, which is similar in construction to the suction control box 64 except that the passage 77 communicates with the tube 170 instead of with the interior of a bellows. The suction box also communicates

40 through a tube 172 with the main suction box 86 and is provided with a suction control tube 173 under the control of the cam shaft 103 similarly to the tube 93. Upon the admission of atmospheric air to the suction control tube 173, the suction box 86 is connected through the suction control box 171, flexible tube 170, hollow supporting rod 169, hollow arms 168 of the frame 167 and openings 166 in the flat box 163. The upper wrapper 165 is there-
45 by drawn tightly against the bottom surface 164 of the box 163 through the suction transmitted through openings 174 in the bottom wall 164, so that, upon lifting the box 163 the wrapper 165 is lifted and may be car-

50 ried by the box 163 to a position immediately above the article 50 to be wrapped, the wrapper immediately beneath the top wrapper being retained in position by the lips 160 and 161.

55 60 65 To enable the supporting tube or hollow

rod 169 to be lifted and to lift the suction or gripping box 163 preparatory to transferring the upper wrapper 165, the rear end of the tube 169 is slidably supported in hollow supporting sleeve 175, Figs. 6 and 8, the rear end of which is mounted in a rock beam 176 fulcrumed between a pair of uprights 177 at the rear end of the frame of the machine. A sliding connection is provided between the tube 169 and the flexible tube 170 by means of a short connecting tube 178 secured at one end to the tube 170 and telescoping into the rear end of the tube 169.

70 75 80 85 90 95 100 105 110 115 120 125 The sleeve 175 is lifted about the end fulcrumed on the uprights 177 by means of a bellows 179 mounted on and connected to a control box 180 of the construction described above and having a movable operating wall 181. The wall 181 is provided at its lower, hinged end with a projecting bracket 182 the free end of which is connected through a link 183 to a supporting cradle 184 for the free end of the sleeve. The cradle 184 normally rests on a supporting plate 185 on the frame of the machine, but when the interior of the bellows 179 is connected to the suction box 86 through the control box 180, the wall 181 is swung, tilting the free end of the bracket and the link 183 upwardly and lifting the cradle 184 and sleeve 175. The box 163 is then in position to be moved rearwardly.

100 105 110 115 120 125 The tube 169, frame 167 and lifting box 163 are moved rearwardly by means of a bellows 186, Fig. 6, at the rear of the machine which is connected to suction through a supporting control box 187 and has a movable wall 188 from which movement is transmitted to the tube 169 when the bellows 186 is collapsed. The movement of the wall 188 is transmitted through a link 189 and link 190 to a lever 191 pivoted at its lower end in a supporting ear 192 and at its upper end connected through a link 193 to a lug 194 depending from the tube 169 through a slot 195 in the sleeve 175. Through this mechanism, the box 163 is transferred to a position immediately above the piece 50 on the plunger plate 125. The connection of the tube 170 through the control box 171 to the suction box 86 is then closed and atmospheric air is admitted to the tube 170 and through its connections to the box 163 releasing the wrapper 165. The box 163 is then returned to its original position above the pack of wrappers 152 and out of the way of subsequent wrapping operations. To enable air to penetrate between the bottom wall 164 of the box 163 and the wrapper to permit a quick release of the wrapper, channels may be cut in the bottom surface of the bottom wall as indicated in Fig. 8. To return the box 163 to its original position, the tube 169 is driven through a

return movement by means of a bellows 196 above bellows 186 and having a control box 197 and a movable wall 198 connected to the link 190 by means of a bracket arm 199. It will be understood that the operations of the boxes 187 and 197 are such that one is connected to the suction box 86 immediately as the other is disconnected therefrom.

At the time the wrapper 165 is released from the box 163 above the plunger plate 125, it is gripped at its lower surface and drawn downwardly onto a platform 200, Figs. 5, 6, 8 and 15, by means of suction transmitted from a pair of hollow arms 201 through openings 202 in the upper wall of the frame. When the wrapper is thus held on the platform 200 it spans a central opening 203 between the arms 201 and of a size to permit the piece 50 and plunger plate 125 to be raised therethrough. Suction is transmitted to the arms 201 from the main suction box 86 through a control box 204 connected to the arms 201 by means of a tube 205 and a yoke 206. The control box 204 is actuated to connect the arms 201 to the suction box as the suction is released from the travelling box 163. The wrapper 165 is thus held firmly in position on the platform 200 above the article 50 on the plate 125 so that when it is folded about the piece the printed matter is uppermost. The supporting frame 167 of the plate 163 is of such a size that, when the plate 163 is returned to its position above the stack of wrappers 152, a space 207 is left above the opening 203 to permit the wrapper and article being wrapped to be pushed upwardly therethrough. With the article 50 properly centered on the plunger plate 125 and the wrapper 165 properly positioned on the platform 200 as above described, they are ready for the wrapping operations.

In the wrapping operations, the plunger plate 125 and article 50 to be wrapped are pushed upwardly by a vertically slidable plunger 208 beneath and supporting the plate 125, the article 50 being thus brought into contact with the under surface of the wrapper 165, as indicated in Fig. 19. Upon its further upward movement, the article 50 lifts the wrapper 165 at its longitudinal center line, the portions of the wrapper at each side of the article being held from upward movement by the suction applied along the arms 201 and through the openings 202. The wrapper is, accordingly, drawn inwardly and tightly about the upper and side portions of the article 50 as shown in Fig. 20. Upon the further upward movement of the article 50 and wrapper 165 they pass between a pair of spaced, upwardly converging guide plates 209 and 210 mounted on the ends of a pair of slides 211 and 212, Fig. 9, at right angles to the longitudinal axis of the article 50 and slidably mounted in guides 213 and 214. The slides are urged inwardly toward each other by means of springs 215 and 216 between the outer ends of the slides 211 and 212 and fixed stops 217 and 218, respectively, to hold the guide plates 209 and 210 against the outer surface of the wrapper lying against the sides of the piece 50 and thus draw the wrapper tightly against the top and sides of the piece 50 to be wrapped. The inner movement and spacing of the guide plates 209 and 210 are limited to enable the piece to enter between the lower edges of the plates by means of pins 219 and 220 having heads abutting the outer ends of the stops 217 and 218 and passing through these stops and through and supporting the springs 215 and 216 and secured to the ends of the slides 211 and 212.

At the upper portion of its path of travel the article 50 passes between a pair of horizontal spaced supporting plates 221 and 222 mounted on upwardly projecting lugs 223 and 224, Figs. 25 and 26, on the inner ends of the slides 211 and 212 and thus movable with the converging guide plates 209 and 210 to enable the article 50 to pass therebetween. The article 50 reaches the upper limit of its movement just above the inner edges of the holding plates 221 and 222, which thereupon are released and pressed inwardly beneath the bottom edges of the article 50 through the action of the springs 215 and 216 on the ends of the slides 211 and 212, the inner edges of the plates 221 and 222 being beveled as at 225 to enable the plates to press the wrapper 165 inwardly between the bottom edges of the article 50 and the plunger plate 125 and hold the article 50 independently of the plunger plate. The plunger plate 125 and plunger 208 are then lowered, leaving the article 50 supported on and between the horizontal holding plates 221 and 222. The article 50 is held in position and the wrapper 165 tightly spread against the surfaces of the piece by means of a pair of brushes 226 and 227 secured at their backs on suitable brackets 228 and 229 and with their bristles projecting inwardly towards each other and bearing against the surfaces of the wrapper covering the sides of the article 50.

In their vertical movements, the plunger 208 and plunger plate 125 slide through and are guided in an opening 230 in the feedway 59 and its supporting beam 231 and the plunger is guided at its lower end in guides 232 extending upwardly from a cross beam 233 of the supporting frame of the machine. The plunger 208 is moved upwardly and downwardly by means of a pneumatic bellows 234, Fig. 1, having a suction and control box 235 connected through a tube 236 to a common suction box 86 and having a control tube, not shown, controlled by the cam shaft 103 similarly to that of bellows 62. Because of the greater power required to

operate the plunger, the box 235 is larger than the box 64, or three boxes of the size of the box 64 are used in parallel. The bellows 234 is also provided with a movable wall 237 from which the driving movement is transmitted through a suitable transmission mechanism to the plunger 208. To insure the movement of the plunger to the limit of its path with exactness and certainty and to provide a firm support on the plunger for a lever operated in a subsequent operation, the power of the bellows 234 is exerted through a suitable toggle mechanism.

15 To this end the movement of the wall 237 is transmitted through a link 238, pivoted on a bracket 239 on the free end of the wall 237, to a pair of toggle levers 240 and 241, the lower of which is pivoted at its lower end in a bracket 242 on a fixed supporting beam 243. The upper end of the upper toggle lever 241 is pivoted to a lever 244 fulcrumed on a bracket 245 depending from a fixed supporting beam 233 and as the 20 toggle is straightened by the movement of the link 238 it imparts an upward movement to the free, forward arm of the lever 244. The upward movement of the lever 244 is transmitted through a link 247 to a lever 248, fulcrumed at its rear end in a bracket 249 on a fixed supporting upright 250 and extending at its forward end to an opening or space 251 in the plunger 208, Fig. 5. From the forward end of the lever 248 the 25 upward movement is transmitted to the plunger 208 through a pair of spaced links 252 pivotally connected at their lower ends to the free end of the lever 248 and at their upper ends connected to a cross pin 253 of the piston 208. The levers 244 and 248 are so proportioned that when the toggle levers 240 and 241 are straightened, the upper surface of the plunger plate 125 is just above the holding plates 221 and 222. To cushion 30 the movement of the plunger as it approaches its upper limit of movement so as to prevent shock, the lever 244 is extended rearwardly of the fulcrum 245 to form an arm 254 on the end of which is mounted a friction block 255 positioned to slide between and frictionally engage the inner surfaces of a pair of fixed cushioning springs 256.

The lowering movement is imparted to the plunger 208 immediately upon the completion of its upper movements, by means of a bellows 257 on the opposite side of the toggle levers 240 and 241 from the bellows 234 having a fixed plate and suction box 258 mounted on a standard 259 and having 35 a movable wall 260 connected by a link 261 to the toggle levers 240 and 241 and movable reversely to the wall 237. The suction boxes 235 and 258 are so controlled from the cam shaft 103 that suction is alternately 40 simultaneously disconnected from one and

connected to the other and are timed to raise and lower the plunger 208 at the proper intervals. As the plunger 208 is lowered in the manner, it leaves the article 50 supported at its side edges and with the under surface exposed and with side edge portions 262 and 263 of the wrapper 165 hanging downwardly from the side edges of the article 50 in position to be tucked therebeneath, as shown in Fig. 37.

75 The forward edge portion of the wrapper 165 is tucked rearwardly beneath and against the under surface of the article 50 by means of a tucker or folding plate 264 slidable between guides 265, Fig. 10, on a supporting plate 266 and between the upper edge of the guide plate 209 and the under surface of holding plate 221 and having a notch 267 at its free end to receive the upwardly projecting lug 223. The proper 80 movement is imparted to the plate 264 through a suitable transmission mechanism from a bellows 268, Fig. 6, having a rear wall 269 mounted on a suction and control box 270 supported in turn on an upright bracket 271 and having movable front wall 272 connected to the plate 264 by means of a link 273 secured at one end to a bracket 274 on the wall 272 and at its other end to an upright lug 275 on the plate 264. To enable the wrapper to be tucked under from the opposite edge by a tucker plate operated simultaneously and guided at the same level, the under part of that portion of the plate that projects past the guide plate 209 is 85 cut away as at 276, Fig. 23, thus occupying only the upper half of the thickness of the plate lying immediately adjacent the portion of the wrapper that covers the under surface of the article 50. The wrapper is 90 folded by the plate 264 to the position shown in Fig. 38.

95 The rearward depending portion 263 of the wrapper 165 is similarly folded beneath the forward portion 262 by means of a rear tucker plate 277 slidable between guides 278 on the supporting plate 266 and between the upper edge of the guide plate 210 and the under surface of the holding plate 222 and having a notch 279, Fig. 10, at its forward portion to receive the upwardly projecting lug 224 and having the upper half 100 of the forward portion cut away as at 280, Fig. 23, so that it may slide beneath the rearwardly projecting portion of the front plate 264. The plate 277 is reciprocated at the proper intervals by means of an operating bellows 281, Fig. 6, of the construction described above having a suitable suction and control box, not shown, under the control of the cam shaft 103 and having a movable wall 284 from which motion is transmitted to the plate 277 by any suitable mechanism. For this purpose, the movement of 105 the wall is transmitted through a link 286 110

secured at one end to a lug 288 on the wall 284 and at its other end to a crank arm 292 on a rock shaft 293, Figs. 6 and 11, journaled in standards 294 and having a crank arm 295 at right angles to the arm 292 from which horizontal movement is transmitted to the tucker plate 277 through a link 296 secured at one end to the end of the arm 295 and at its other end a lug 297 on the plate 277.

Through the above operations, the wrapper 165 has been wrapped tightly around the top side and under surfaces of the article 50 to be wrapped, as shown in Fig. 39, and the under portions of the wrapper are tightly held by the tucker plates 264 and 277, the end portions of the article 50 being uncovered by the wrapper. The wrapper 165 is of such a size, however, that end portions 298 and 299 are left projecting from the ends of the article 50, as in Fig. 24, and forming continuations of the top, side, and bottom walls of the wrapper. In the remaining wrapping operations, these projecting portions of the wrapper are folded to cover the ends of the article 50 and to hold the wrapper in place.

In the first of these end folding operations, the bottom portions 300 and 301 of the projecting portions 298 and 299, comprising the seam 302, are folded upwardly against the ends of the article, thus clamping the seam in position before the plates 264 and 277 are withdrawn. Immediately thereafter, or in the same folding operation following the upward folding of the bottom portions 300 and 301, the side portions 303 and 304 of the projecting ends 298 and 299 are folded inwardly over the folds 300 and 301, leaving only the tops of the projecting portions to be folded in subsequent operations.

To fold the bottom projecting wrapper portions 300 and 301 upwardly, a pair of folding plates 305 and 306 are swung to a vertical position against the opposite ends of the article 50 engaging the wrapper portions 300 and 301 at the end edges of the article 50 and pushing them upwardly against the ends of the article, the side portions 303 and 304 of the wrapper folding inwardly on diagonal edges 307. The plates 305 and 306 at right angles on a pair of swinging levers 310 and 311, respectively, pivoted on upright ears 312 and 313 on the supporting plate 266 in such position as to bring the inner surfaces of the folding plates 305 and 306 against or in close proximity to the ends of the article 50 and fold the wrapper to its position shown in Fig. 40. Immediately succeeding the upward folding of the portions 300 and 301, the remaining side projecting portions 303 and 304 are folded inwardly by means of a pair of plates 314 and 315 pivoted on vertical pintles 316 and

317 projecting upwardly from the plate 266 at, and slightly spaced from, the corners of the article 50, there being a pair of plates 314 and 315 at each end of the article. The plates 314 and 315 are of such dimensions as to swing against the outer faces of the plates 305 and 306 with their inner edges slightly spaced from each other, the projecting upper surface of the wrapper folding on the lines 318 and 319 as indicated in Fig. 28.

The levers 310 and 311 and swinging plates 314 and 315 at each end of the article are actuated through suitable transmission mechanisms from a pair of bellows 320, each having a fixed wall 321 and suction control box 322 mounted on a standard 323, one at each side of the machine, and as these bellows and transmission mechanisms are duplicates, identical numerals are applied to corresponding elements of the opposite mechanisms. The transmission mechanisms of the bellows 320 are so arranged as to first impart a swinging movement to the levers 310 and 311 and, upon the continued movement of the bellows mechanisms, after the completion of the movements of the levers 310 and 311, to swing the plates 314 and 315 against the outer faces of the plates 305 and 306, thus avoiding the use of two sets of bellows and control and transmission mechanisms for the operation of the side and bottom folding mechanisms.

For this purpose, the movement of a moving wall 324 of the bellows 320 is transmitted through a link 325, Figs. 5 and 11, secured at one end to an ear 326 on the wall 324 and at its other end secured to a lug 327 projecting upwardly from a sliding plate 328 slidably mounted in guiding grooves 329 on the plate 266. The sliding movement thus imparted to the plate 328 is transmitted to the levers 310 and 311 through a spring 330, Figs. 5, 11, 25, 26, 27, 28 and 29, secured at one end to a lug 331 projecting upwardly from the plate 328 and extending through an enclosing tube 332, which tube is also secured at one end to the lug 331, and at its other end by a fork 333 to an ear 334 projecting upwardly from the ends of the lever 310 or 311, respectively. The tension of the spring 330 is such as to hold the end of the fork 333 tightly against the end of the tube 332 as the plate 328 and lug 331 move from the position indicated in 1 to the position indicated in 2 of Fig. 29, this movement serving to swing the levers 310 and 311 to a horizontal position and swinging the folding plates 305 and 306 to vertical, folding, positions. At position 2 the fork 333 rests on a stop 335, Fig. 25, which limits and prevents further movement of the levers 310 and 311.

During this movement of the transmission elements and levers 310 and 311, the swinging folding plates 314 and 315 are

- held in open, non-folding, positions by complete the wrapping of the article. In the means of springs 336 and 337, secured at the final wrapping operations, moreover, the one end to pins 338 and 339, respectively, projecting from the supporting plate 226 and stretched between the pins 338 and 339 and pins 340 and 341 on reciprocable rods 342 and 343, which are secured at one of their ends to arms 344 and 345 projecting outwardly and angularly from the folding 70 plates 314 and 315, which are thus held in open position by the tension of the springs 336 and 337, respectively transmitted through the rods 342 and 343. The free ends of the rods 342 and 343 are guided between wings 10 346 and 347 projecting sidewise from the lugs 331 and by pins 348 and 349 extending from the wings 346 and 347, respectively, through longitudinal slots 350 and 351 in the rods 342 and 343. During the movement of the 15 plate 328 and lug 327 from position 1 to position 2, the pins 348 and 349 slide freely in the slots 350 and 351, permitting the movement of the transmission elements to lift the folding plates 305 and 306 while leaving the sidewise folding plates 314 and 315 in open position.
- As the pins 348 and 349 reach the ends of the slots 350 and 351 as indicated in position 2 of Fig. 29, the further movement of 20 the lugs 331 and pins 348 and 349 carries the rods 342 and 343 with the pins bringing the pins and rods to the position 3 of Fig. 29. In this movement of the rods 342 and 343, the plates 314 and 315 are swung from 25 their open positions to positions against the ends of the article 50 as indicated in position 3 of Fig. 29 and thus folding inwardly the sidewise extending portions 303 and 304 of the wrapper. Upon the completion of these 30 folding operations and the admission of air under atmospheric pressure to bellows 320 the rods 342 and 343 and lugs 331 are drawn to position 2 by the springs 336 and 337 thus 35 swinging the plates 314 and 315 to open position and thereafter the lugs and the folding plates 305 and 306 move to position 1 by the weight of the plates 305 and 306 and the levers 310 and 311.
- Through the above folding operations the 40 wrapper has been wrapped about the top, side, and bottom walls of the article 50 and the projecting ends of the wrapper have been folded upwardly and sidewise to cover the ends and hold the bottom seam of the 45 wrapper the wrapper being then in the position shown in Fig. 41. The tucker plates 264 and 277 may then be withdrawn without danger of the seam opening, particularly as the brushes 226 and 227 serve to hold the 50 side portions of the wrapper against the sides of the article 50. There still remains, however, portions 352 and 353 of wrapper projecting from each end of the top portion 55 of the wrapper beyond the ends of the article 50, which must be folded downwardly to
- held in open, non-folding, positions by complete the wrapping of the article. In the means of springs 336 and 337, secured at the final wrapping operations, moreover, the one end to pins 338 and 339, respectively, projecting from the supporting plate 226 and stretched between the pins 338 and 339 and pins 340 and 341 on reciprocable rods 342 and 343, which are secured at one of their ends to arms 344 and 345 projecting outwardly and angularly from the folding 70 plates 314 and 315, which are thus held in open position by the tension of the springs 336 and 337, respectively transmitted through the rods 342 and 343. The free ends of the rods 342 and 343 are guided between wings 10 346 and 347 projecting sidewise from the lugs 331 and by pins 348 and 349 extending from the wings 346 and 347, respectively, through longitudinal slots 350 and 351 in the rods 342 and 343. During the movement of the 15 plate 328 and lug 327 from position 1 to position 2, the pins 348 and 349 slide freely in the slots 350 and 351, permitting the movement of the transmission elements to lift the folding plates 305 and 306 while leaving the sidewise folding plates 314 and 315 in open position.
- As the pins 348 and 349 reach the ends of the slots 350 and 351 as indicated in position 2 of Fig. 29, the further movement of 20 the lugs 331 and pins 348 and 349 carries the rods 342 and 343 with the pins bringing the pins and rods to the position 3 of Fig. 29. In this movement of the rods 342 and 343, the plates 314 and 315 are swung from 25 their open positions to positions against the ends of the article 50 as indicated in position 3 of Fig. 29 and thus folding inwardly the sidewise extending portions 303 and 304 of the wrapper. Upon the completion of these 30 folding operations and the admission of air under atmospheric pressure to bellows 320 the rods 342 and 343 and lugs 331 are drawn to position 2 by the springs 336 and 337 thus 35 swinging the plates 314 and 315 to open position and thereafter the lugs and the folding plates 305 and 306 move to position 1 by the weight of the plates 305 and 306 and the levers 310 and 311.
- Through the above folding operations the 40 wrapper has been wrapped about the top, side, and bottom walls of the article 50 and the projecting ends of the wrapper have been folded upwardly and sidewise to cover the ends and hold the bottom seam of the 45 wrapper the wrapper being then in the position shown in Fig. 41. The tucker plates 264 and 277 may then be withdrawn without danger of the seam opening, particularly as the brushes 226 and 227 serve to hold the 50 side portions of the wrapper against the sides of the article 50. There still remains, however, portions 352 and 353 of wrapper projecting from each end of the top portion 55 of the wrapper beyond the ends of the article 50, which must be folded downwardly to
- To fold the projecting portions 352 and 353 downwardly over the ends of the article, the plunger plate 125 is lifted to a position to reach and support the bottom of the article 50 as shown in Fig. 21 and is then lifted further to lift the article 50 between a pair of guide and pressing plates 354 and 355 supported on slides 356 and 357 slidably supported in guides 358 and 359 on the under face of a supporting plate 360, Fig. 5, at each end of the article and pressed inwardly against the ends of the article by means of springs 361 and 362 confined between the ends of the slides 356 and 357 and lugs 363 and 364 depending from the under surface of the plate 360. The guiding and pressing plates 354 and 355 are inclined toward each other at their upper ends so as to receive the articles 50 and exert pressure as 80 the articles move upwardly. The plates 354 and 355 are held in the proper spaced positions to freely receive the articles between their lower edges by means of rods 365 and 366, respectively which project from 85 the ends of the slides through the lugs 363 and 364 and are provided at their free ends with heads 367 and 368 to abut the outer ends of the lugs. As the article 50 is lifted between the guide and pressing plates 354 and 355, the plates 354 and 355 and slides 356 and 357 are pressed apart against the pressure of the springs 361 and 362 and the article is lifted to a position just above a pair of central retaining lugs 369 and 370, 100 Fig. 30, extending upwardly and inwardly from the upper edges of the plates 354 and 355 to retain the article 50 when the plunger plate 125 is lowered.
- In lifting the article 50 between the guide 105 and pressing plates 354 and 355, the plunger 208 is first lifted to its uppermost position by the action of the bellows 234 transmitted through the link 238, toggle 240 and 241, lever 254, link 247, lever 248 and links 252 to 110 its uppermost position as described above. Through the toggles 240 and 241, the plunger is positively and firmly locked in its uppermost position and may thus serve as a firm and unyielding fulcrum support for 115 subsequent movements of the plunger plate mechanism.
- To enable the plunger plate 125 to lift the article 50 above the upper limit of movement of the plunger 208 the plate 125 is 120 made independent of the plunger 208 and is lifted and guided by means of a pair of supports 371 and 372, Fig. 5, forming downward continuations of the plate 125 sliding over the sides of the plunger 208 and guided 125

by the sides of the plunger 208 and by side fingers 373 mounted on the plunger and engaging the edges of the supports 371 and 372. The plate 125 is normally held down 5 on the top of the plunger 208 by means of a pair of springs 374, Figs. 3 and 6, which are at one of their ends secured to the plunger 208 by means of hooks 375 and at their other ends are hooked through ears 376 on the outer upper ends of levers 377 which are fulcrumed on a bracket 378 projecting from the plunger 208 and the lower ends of which are connected to ears 379 on the supports 371 and 372 by means of connecting links 380. The outer, upper ends of the levers 377 are connected by a cross piece 381 to secure uniformity of movement.

When the plunger 208 is lifted the plunger plate 125 and the standards 371 and 372 and 20 the levers 377, bracket 378 and links 380 are lifted therewith. To secure a final lifting movement of the plate 125 relative to the plunger 208, the outer end of the lever 377 is depressed against the tension of the spring 374 by pressure exerted on the plate 381. The force for thus tilting the lever 377 is transmitted from a bellows 382 rigidly mounted on a fixed suction control box 383 connected by a tube 384 to the suction box 30 86 and having a movable wall 385 from which movement is transmitted for operating the levers 377. The movement of the wall 385 is received by a vertical link rod 386 secured at its lower end to an ear 387 35 on the wall 385 and at its upper end to a crank arm 388 rigidly mounted on a rock shaft 389 journaled in a bracket 390 depending from the beam 134 of the supporting frame of the machine. A crank arm 40 392, Fig. 6, is also rigidly mounted on the rock shaft 389 in a position overlying and immediately above the connecting plate 381 of the levers 377 which by the upward movement of the plunger 208 has been raised to the position indicated in dotted lines in Fig. 6. As the bellows 383 is deflated and the movable wall 385 and link rod 386 are lowered, the rock shaft 389 is rocked through the crank arm 388 in a direction to lower 45 the end of the crank arm 392 and cause it to press downwardly on the cross plate 381, the end of the arm 392 being provided with a roller 393 which bears on the plate 381. As the plate 381 is pressed downwardly the 50 plunger plate 125 is lifted from the top of the plunger 208 by the action of the levers 377 links 380 and supports 371, the plunger 208 and bracket 378 being held firmly in position by the toggles 240-241 against the 55 depressing action of the lever 392 which would otherwise tend to counteract the force of the plunger bellows 234 and lower the plunger.

When the plunger plate 125 has completed 60 its upward movement and deposited the article 50 on the supporting lugs 369 and 370, the bellows 382 is reinflated with atmospheric air, lifting the rod 386 and permitting the rock shaft 389 to rock in reverse movement and lift the crank arm 392, the 70 reverse rocking of the rock shaft 389 being assisted by a counter weight arm 394. As the roller 393 is lifted from the lever plate 381, the levers 377 are drawn to their original positions by the springs 374 and the plate 75 125 is lowered onto the upper end of the plunger 208. At the same time or immediately thereafter, the plunger 208 is lowered in the manner previously described thus lowering the plunger and plate 125 into 80 position to receive a succeeding article for wrapping. To insure the complete return of the plate 125, regardless of the strength of the springs 374, the upper ends of the levers 377 are positioned to rest on projections 395 on the bracket 249 and in case the plate 125 has not been completely returned to the top of the plunger 208 to strike the lower edge of the levers 377 and thus positively return the plate 125 to its lowermost 90 position resting on the top of the plunger.

Through the above operation, the wrapped article has been lifted through the guide and pressing plates 354 and 355 and released and supported on and above the central inwardly 95 projecting supporting lugs 369 and 370 of the plates 354 and 355 and the wrapper has been folded to the position shown in Fig. 42. To hold the end folds in position tightly 100 against the ends of the article, a pair of downwardly opening plates 396 and 397 are provided immediately above the lugs 369 and 370 having upward continuations bent to form outwardly projecting bight or bay portions 398 and 399 and upward extensions 105 400 and 401. The plates 396 and 397 are pivotally supported by pivots 402 and 403 at the lower ends of the extensions 400 and 401, respectively, journaled in lugs 404 and 405 on a supporting plate 406, and are 110 pressed inwardly against the ends of the wrapped article 50 by means of a spring 407 confined between the upper extensions 400 and 401 and held in place by pins 408 projecting inwardly from the upper ends of the extensions 400 and 401. The pressure of the spring 407 on the upper extensions 400 and 401 presses the plates 396 and 397 resiliently 115 inwardly against the ends of the article 50 to hold the folds in place during subsequent folding and securing operations.

The end folds formed by the above operations may be secured in any suitable or desired manner. In the present example, the wrapper 165 is of such length or dimensions 120 that after the above folding operations folded end portions 410 and 411 are left depending downwardly from the lower end edges of the wrapped article. These depending portions are folded and pressed 125 130

65 its upward movement and deposited the ar-

against the bottom surface of the portions 262 and 263 of the wrapper thus holding the end folds in position. To prevent the bottom folded portions 262 and 263 from bulging outwardly or downwardly as the end depending portions 410 and 411 are folded under the article, a pair of lever arms 414 and 415, pivoted on lugs 416 and 417, respectively on the supporting plate 360 are swung inwardly to carry supporting plates 418 and 419 mounted on the ends of the levers 414 and 415 upwardly under the bottom of the wrapped article 50 and hold the bottom wrapper portions 262 and 263 and the seam in position. The lever arms 414 and 415 are swung upwardly and held in position by means of links 420 and 421 connecting lugs 422 and 423 on the lever arms to lugs 424 and 425, respectively, on the reciprocating links 273 and 296, Fig. 6, which operate the tucker plates 264 and 277, the lever arms 414 and 415 being, accordingly, swung upwardly while a wrapper is being tucked under a succeeding article, and a common motive source being used for both operations.

While the plates 418 and 419 are thus swung and held against the bottom of the wrapped article, the depending end portions 410 and 411 of the wrapper are tucked beneath the wrapped article by means of a pair of tucker plates 426 and 427, Figs. 12, 13 and 30, slidably mounted in guiding grooves 428 and 429 on the supporting plate 360 and provided with notches 430 and 431, respectively, at their inner edges to enable them to pass the article supporting lugs 369 and 370. The inner edges of the plates are also preferably cut inwardly as at 432 and 433 to hold the depending wrapper portions 410 and 411 inwardly and prevent them from spreading as they are folded. When the holding plates 418 and 419 and tucker plates 426 and 427 are moved to their positions under the wrapped article, they occupy approximately the positions shown in Fig. 32 supporting the entire bottom surface of the article.

The tucker plates 426 and 427 are moved into tucking position by means of an operating bellows 434 on opposite sides of the machine each having a fixed wall 435 and suction control box 436 mounted on an upright 437 and controlled by the cam shaft 103 and connected to the suction box 86 in the usual manner. The movement of a movable wall 438 of the respective bellows 434 is transmitted from an ear 439 on the wall 438 through a connecting link 440 to an ear 441 projecting upwardly from the tucker plate 426 or 427. Through the movement of the tucker plates 426 and 427 the wrapper is folded to the form shown in Fig. 43. The supporting plates 418 and 419 are then lowered out of position and the tucker plates 426 and 427 are withdrawn leaving the

wrapped article freely supported on the lugs 369 and 370 and between the plates 396 and 397.

During the completion of the above wrapping operations of the article supported on the lugs 369 and 370, a succeeding article has been wrapped on the lower supporting plates 221 and 222 and is ready to be lifted upwardly between the guiding and pressing plates 354 and 355. As the succeeding article is lifted it passes through the position indicated by D of Fig. 34 to the position C of Figs. 31 and 32, pushing the wrapped article through the positions B. As the wrapped article reaches position B of Fig. 32, it is received between a pair of upright extensions 438 and 439 and slightly offset outwardly from the plates 396 and 397 so that it is guided without being frictionally held from movement.

From the position B the wrapped article is slid onto an outlet guideway 440 having a downwardly curved forward edge 441 to prevent the wrapped articles from catching on this edge. The wrapped article is moved onto the guideway 441 by means of a vertical transverse plate 442 having forwardly projecting ears 443 resting on and secured to a transverse carrying arm 444, which is in turn carried on the end of a longitudinal rod 445 slidably supported in guiding lugs 446 on the sides of the guideway 440. To slide the wrapped article onto the guideway 440 the rod 445 is given an appropriate longitudinal movement from a crank arm 447 rigidly mounted on and projecting upwardly from, the rock shaft 293, which operates the tucker plate 277, through a link 448 connected between the upper end of the arm 447 and to a lug 449 adjustably mounted on the rod 445. Through the movement of the rock shaft 293 and crank arm 447 the plate 442 is moved to slide the wrapped article into the position B of Fig. 32 on the guideway 440 simultaneously with the wrapping of a later article, a preceding article being pushed forwardly as at A. To prevent the wrapped articles from piling up near the discharging plate 442, the guideway 440 is inclined downwardly at 450 a short distance from the wrapping mechanism.

When the article 50 has been thus pushed onto the guideway 440, the rod 445 and plate 442 are returned to their original positions by means of a spring 451 confined about the rod 445 between one of the lugs 446 and a collar 452 adjustably fixed on the rod 445. To prevent a wrapped article from being thrown too high when the plate 442 is in receiving position, a stopping plate 453 is formed as a rearward extension from the top of the plate 442. The position of the plate 442 on the rod 445 may be adjusted by means of a set screw 454 and the height of the plate 442 and extension 453 are adjusted

by means of washers 455. The possibility of an article being thrown upwardly while the plate 442 is in discharging position as indicated in Fig. 32 and thereupon becoming caught by the return movement of the plate 442 is guarded against by a pair of stop plates 456 projecting forwardly from the lower edge of the plate 442.

In the above mechanism the moving elements are driven from individual pneumatically operated motive elements, preferably in the form of bellows connected to a suitable suction means. The bellows may be connected to a common suction tank 86 by means of separate and individual tubes as described above or in other suitable manner but in the preferred form of the invention, the suction is transmitted through a hollow frame work, which serves to support the various elements and at the same time act as a suction tank or chamber, and which may be connected to the various motive means by short lengths of tubing. As illustrated in Fig. 44, this frame may be formed of hollow uprights 458 supported on castors 459 and supporting a series of hollow square frames 461, 462 and 463, communicating with the interiors of the uprights 458 and to one of these frames 462 a tube 464 leading to a suction pump or other suitable source of suction may be connected. From the hollow frames 461, 462 and 463, suction may be transmitted to the various bellows through tubes connected to nipples 465 in the frames. With this construction, the necessity of a number of long connecting tubes is obviated.

In the preferred form of the central timing and control means for the suction control boxes of the various motive elements, illustrated in Fig. 45, the stem 101 for lifting the leaf spring 95 and valve pad 94 from the end of the passage 96 bears directly downwardly on the cam shaft 103, which is, for this purpose, supported on a support 465 carrying the guide 102. To permit of an adjustment of the length of the stem 101, it is provided with a rotatable socket member 466 into which is threaded the end of a cam rod 467 which extends from the stem 101 downwardly through a guide 468 to the cam 103 and is provided at its lower end with a cam roller 469. The socket 466 may be locked on the threaded portion of the rod 467 by means of a lock nut 470. The cam shaft 103 may be of any suitable construction, preferably of the construction shown in Fig. 6^a. The surface of the cams may be lubricated by means of oil contained in cups 471 held under the cams and supported on the support 465.

The operation of the apparatus is briefly as follows: Articles 50 to be wrapped are placed on the loading tray 51 and thence

pushed sidewise onto the feeding chute 52 in which the lowermost article is retained by the finger 53, the succeeding articles resting against the side edges of their preceding articles. The bellows 62 is periodically placed in communication with the suction chamber 86, or with the hollow frame of Fig. 44, through the control box 64 under the control of the cam shaft 103, thereby collapsing the bellows and the moving wall 66 of the bellows lowers the arm 69 which first 70 presses downwardly the lever 60 through the spring 71 and then tilts the lever 54 to lift the retaining finger 53 and release the lowermost article 50 while retaining the succeeding articles in the chute 51. After the 80 lowermost article is released, the lever 54 is tilted, through the reinflation of the bellows 62, to lower the finger 53 and lift the lever 60. The released article 50 slides downwardly to the bottom of the chute 51 85 to the feedway 59 and is pushed onto the feedway by the action of the plunger 107 driven by the bellows 109. The article is then pushed along the feedway by a pusher 115 driven by the bellows 116, which pushes 90 the article onto a plunger plate 125 and is then withdrawn by the spring 123 acting through the transmitting lever 119. The article 50 is then centered on the plate 125 by means of a pair of swinging plates 128 95 and 129 pivoted at the rear corners of the plate 125 and driven simultaneously and uniformly by means of a bellows 132 through lever 136, link 137, bell crank lever 138— 141, link 142 and sliding plate 143, which reciprocates links 145 and 146 connecting the plate 143 to the swinging plates 128 and 129 in such a manner as to swing the plates with equal simultaneous movements until they 100 contact with the ends of the article 50. 105

During or immediately after the feeding and centering of the article 50 on the plunger plate 125 the top wrapper 165 of the stack 152 is gripped to the under surface 164 of a carrying plate 163 by means of 110 suction transmitted from the suction box 86 through the tube 170 and supporting tube 168 and through the openings 174. The plate 163 is then lifted by means of a bellows 179 through the lever 183 and a supporting sleeve 175 pivoted at 176, the top wrapper 165 being lifted with the plate 163 and the remaining wrappers being retained by lips 160 and 161 against which they are pressed by the carrying platform 153 which 115 is pressed upwardly by the supporting springs 156 and 157. The plate 163 and tube 170 are then drawn rearwardly by means of the bellows 186 acting through links 189, 190, lever 191, link 193 connected 120 to lug 194 depending from the tube 170 through a slot 195 in the sleeve 175. Through the rearward movement of the tube 125

169 and box 163, the wrapper 165 is carried to a position above the platform 200 and suction openings 202. Suction is then released from the box 163 and applied through 5 the openings 202, thus releasing the wrapper 165 from the box 163 and gripping it onto the platform 200. The box 163 is then returned to its position above the wrapper stack 152 by means of a bellows 197 connected to the link 190. The article 50 and wrapper 165 are now in the position shown in Fig. 36.

The article 50 on the plunger plate 125 is now lifted by a plunger 208, on which the 15 plate 125 rests, by means of the bellows 234 acting through the link 238 toggle levers 240 and 241, lever 254, link 247, lever 248 and link 252. As the article 50 is lifted, it passes through the opening 203 between the 20 arms 201 lifting the wrapper 165 and causing the side portions of the wrapper to be drawn tightly downwardly against the sides of the article as illustrated in Fig. 37. The upward movement of the article 50 and plate 125 continues, the article passing between the guiding plates 209 and 210 and between, and finally resting just above, the supporting plates 221 and 222. The plunger 208 and plunger plate 125 are then lowered 25 by means of the bellows 257 which breaks the toggle 240—241, leaving the article and wrapper supported at the side bottom edges of the article on and between the supporting plates 221 and 222.

30 The depending forward side portion of the wrapper 165 is then tucked inwardly beneath the bottom of the article 50 by means of the tucker plate 264 driven from the bellows 268 through the link 273, thus folding the wrapper to the position shown in Fig. 38. The depending rear wrapper portion is then tucked similarly beneath the article by the tucker plate 277 driven from the bellows 281 through the link 286, crank arm 292, 35 rock shaft 293, arm 295 and link 296, thus folding the wrapper to the position shown in Fig. 39. The bottom portions of the projecting ends of the wrapper are then folded upwardly against the ends of the article by 40 the plate 305 and 306 on the ends of the arms 310 and 311, which are driven from the bellows 320 through the links 325, slide plate 328 and spring 330, the wrapper being thus folded to the position shown in Fig. 40.

45 The sides of the projecting wrapper portions are then folded against the ends of the article by means of the swinging plates 314 and 315, which are swung by the continued movement of the bellows 320 transmitted 50 from the slide 328 through the wings 346 and 347, pins 348 and 349 and rods 342 and 343. The wrapper is thus folded to the position illustrated in Fig. 41. The plates 314 and 315 and 305 and 306 are

then returned to their original positions leaving the wrapper folded as in Fig. 41.

To fold the remaining projecting top portion of the wrapper downwardly the plunger plate 125 and plunger 208 are lifted by the bellows 234 and transmission mechanism to 70 the bottom of the partly wrapped article and the plate 125 is then further lifted above the plunger plate 208 by means of the bellows 382 which imparts a downward pull through the link 386 to the crank arm 388, 75 rocking the rock shaft 389 and arm 392 to depress the plate 381 and levers 377 which have been lifted with the plunger 208 and causing the levers 377, to tilt about their fulcrum 378 and lift the plate 125 relatively 80 to the plunger 208. Upon the lifting of the plate 125, the article 50 is lifted between the resiliently pressed end guiding plates 354 and 355 to a position to rest on the lugs 369 and 370, the wrapper being folded in passing between the plates 354 and 355 to the position shown in Fig. 42 and held in position by the plates 396 and 397 pressed inwardly by the action of the spring 407. The plunger plate 125 is then lowered and the depending 90 end portions of the wrapper 410 and 411 are tucked inwardly beneath the article by the end tucker plates 426 and 427 actuated by the bellows 434 through the link 440 to fold the article to its final form as shown in Fig. 95 43 while the lever arms 414 and 415 and plates 418 and 419 are swung against the bottom of the wrapped article by the links 420 and 421 connecting to the operating mechanism of the tucker plates 264 and 277, 100 which are operating on a succeeding article. The wrapped article is then pushed upwardly by a succeeding wrapped article and is received between the extensions 438 and 439 from whence it is pushed onto the outlet 105 guideway 440 by the plate 442, actuated from the rocker shaft 293 of the tucker operating mechanisms through link 448 and rod 445.

110 As changes of construction could be made within the scope of my invention, it is intended that all matter contained in the above description or shown in the accompanying drawings be interpreted as illustrative and not in a limiting sense.

115 Having described my invention, what I claim and desire to secure by Letters Patent is:

1. Apparatus of the type described which comprises, mechanism for positioning an article in position to be wrapped, mechanism for placing wrapping paper in position relative to said article, mechanism for wrapping said paper about said article, individual and independently operable pneumatic means for operating said mechanisms, and means for actuating said pneumatic operating means in properly timed sequence.

2. Apparatus of the type described which comprises, mechanism for placing an article in a position, mechanism for placing a paper in position to be wrapped about said article, 5 mechanisms for moving said article and said paper through wrapping movements, individual and independently operable pneumatic means for actuating said mechanisms, and means for actuating said pneumatic 10 means from a control in proper timed relation.
3. Apparatus of the type described which comprises, mechanism for placing an article in a position, mechanism for placing a paper 15 in position to be wrapped about said article, mechanisms for moving said article and said paper through wrapping movements, individual and independently operable pneumatic means for actuating said mechanisms, 20 and a common control means for individually establishing and breaking pneumatic connections to said pneumatic operating means in proper timed relation.
4. Apparatus of the type described which 25 comprises mechanism for placing an article in position, mechanism for placing a wrapper in position to be wrapped about said article, mechanisms for moving said article and said wrapper through wrapping movements, 30 individual and independently operable pneumatic means for actuating said mechanisms, individual means for each of said pneumatic means for establishing and terminating pneumatic connections to said 35 pneumatic operating means and a cam for operating said pneumatic connecting means in a definite timed relation.
5. Apparatus of the type described which 40 comprises, means for feeding an article to a position for wrapping, means for positioning a wrapper above said article in said wrapping position, means for lifting said article with said wrapper, means for tucking the side portions of said wrapper under 45 said article, means for tucking the projecting end portions of said wrapper against the ends of said wrapper, individual, pneumatically operated, motive means for said means, and a common control device for said motive means.
6. Apparatus of the type described which 50 comprises, a feed way, a plunger in said feed way, means for feeding an article through said feed way onto said plunger, a pair of plates pivoted to swing towards the center of said plunger, a pneumatic actuating means for swinging said plates, and a transmission means for imparting equal and simultaneous movements from said actuating means to said plates.
7. Apparatus of the type described which 55 comprises, a feed way, a pair of spaced brushes one at each side of said feed way, a vertically reciprocable plunger between said brushes, a pair of swinging plates for cen- 60 tering an article on said feed way between said brushes, a sliding plate, a pair of links connecting said slide equally to said swinging plates, and a pneumatic means for operating said slide.
8. Apparatus of the type described which 65 comprises, a pair of spaced holding brushes, a vertically reciprocable plunger between said brushes, a pair of plates pivoted to swing from the ends of one of said brushes to the center of said plunger, a pneumatically operated bellows and means for transmitting movement from said bellows equally and uniformly to said swinging plates.
9. Apparatus of the type described which 70 comprises, a platform having an opening and a pair of suction arms at opposite edges of said opening, means for transferring a wrapper and placing it on said platform centrally of said opening, a plunger movable vertically through said opening, and means for placing an article on and centering it on said plunger.
10. Apparatus of the type described which 75 comprises, a platform having an opening therein and suction means at opposite edges of said opening, a suction box having openings in its bottom wall, pneumatically operated means for moving said box above said platform and releasing the suction from said box while applying suction to said platform suction means, a plunger movable vertically through said opening, and means for placing and centering an article on said plunger.
11. Apparatus of the type described which 80 comprises, a platform having an opening therein and having hollow suction arms on opposite sides of said opening, a suction box having openings in its bottom, a hollow frame supporting said box and movable to place said box above said opening and at a distance from said opening and having a space above said opening when in the latter position, pneumatic operating means for said 85 frame, a plunger movable vertically through said opening, and pneumatic actuating means for said plunger.
12. Apparatus of the type described which 90 comprises, a pair of guiding plates, a pair of supporting means above said guiding plates, supporting slides for said guiding plates and supporting means, means for pressing said slides inwardly towards each other, a plunger for supporting an article, 95 means for positioning and supporting a wrapper above said article, means for raising said plunger and lift said article between said guiding plates to rest on said supporting means, and tucker plates slidable inwardly between said supporting means and said guiding plates.
13. Apparatus of the type described which 100 comprises, a plunger, a pair of spaced, upwardly converging guide plates above said

- plunger, a pair of supporting plates mounted above and carried with said guide plates, means for resiliently pressing said guide plates and supporting plates towards each other, means for supporting a wrapper between said plunger and supporting and guide plates, and a pair of tucker plates 50 slidable inwardly between said guide plates and said supporting plates.
- 10 14. Apparatus of the type described which comprises, a pair of spaced, upwardly converging guide plates, a pair of supporting plates mounted above and carried with said guide plates, means for resiliently pressing said guide plates and supporting plates as units towards each other, a plunger, lifting means for said plunger comprising a toggle to lift the surface of said plunger just above said supporting plates as said 15 toggle is straightened, and pneumatic means for straightening and breaking said toggle.
- 15 15. Apparatus of the type described which comprises, a pair of spaced, upwardly converging guide plates, a pair of supporting plates mounted above and carried with said guide plates, means for resiliently pressing said guide plates and supporting plates as units towards each other, a plunger, lifting means for said plunger comprising a toggle to lift the surface of said plunger just above said supporting plates as said 20 toggle is straightening said toggle and a pneumatically operated bellows for breaking said toggle.
- 30 16. Apparatus of the type described which comprises, a pair of spaced, upwardly converging guide plates, a pair of supporting plates above and carried with said guide plates, means for pressing said plates as units toward each other, means for supporting a wrapper beneath said guide plates, means for lifting an article upwardly beneath said wrapper and between said guide plates to rest on said supporting plates and 40 tucker plates slidable inwardly between said guiding plates and said supporting plates.
- 45 17. Apparatus of the type described which comprises, a pair of spaced supporting plates, a pair of tucker plates, and aligned guides for said tucker plates, in which said tucker plates slide towards each other, the upper portion of one tucker plate and the lower portion of the other tucker plate being cut away near their adjacent edges to 55 permit said portions to overlap as said plates are brought together.
- 50 18. Apparatus of the type described which comprises, a pair of spaced supports, aligned guides beneath said supports, and a pair of tucker plates slidable in said guides inwardly past the edges of said supports, the lower portion of one plate and the upper portion of the other plate sliding past said supports being cut away to enable said 60 plates to overlap.
19. Apparatus of the type described which comprises, a pair of spaced supports, a pair of spaced, guide plates, one beneath and carried with each of said supports and diverging downwardly from the edges of said supports, means for pressing said guide plates and supports towards each other, means for supporting a wrapper beneath said guide plates, means for lifting an article upwardly carrying said wrapper between said guide plates to rest on and between said supports, tucker plates slidable between said guide plates and supports beneath said supported article and means for tucking the projecting ends of said wrapper against the ends of 65 said supported article.
20. Apparatus of the type described which comprises, a pair of guide plates inclined upwardly towards each other, sliding supports for said guide plates having upright lugs, means for pressing said supports resiliently toward each other, horizontal supporting plates mounted one on each lug, and tucker plates slidable between said guiding and supporting plates and notched to receive said lugs.
- 25 21. Apparatus of the type described which comprises, a pair of guide plates inclined upwardly toward each other, sliding supports for said guide plates having upright lugs, means for pressing said supports resiliently toward each other, means to limit the inward movement of said supports, horizontal supporting plates mounted one on each lug, and tucker plates slidable between 30 said guiding and supporting plates and notched to receive said lug.
- 35 22. Apparatus of the type described which comprises, a pair of guide plates inclined upwardly toward each other, inwardly pressed sliding supports for said plates, supporting means mounted one on each of said supports slightly above the top edges of said plates, pneumatically driven means for lifting an article and a wrapper thereon between said plates to rest on said supporting means, a pair of tucker plates slidable inwardly between said guide plates and said supporting means to overlapping positions beneath said supported article and pneumatic means for sliding said tucker plates.
- 40 23. Apparatus of the type described which comprises, a lower wrapping mechanism, an upper wrapping mechanism, a plunger slidable upwardly to said lower wrapping mechanism, a plunger plate supported on and liftable above said plunger, a lifting means for said plunger comprising a toggle to lift said plunger plate to said lower wrapping mechanism when straightened, pneumatic means for straightening and breaking said toggle, and means supported on said plunger for lifting said plunger plate to said upper wrapping mechanism while said plunger is in raised position.

24. Apparatus of the type described which comprises, a lower wrapping mechanism, an upper wrapping mechanism, a plunger, a plunger plate supported on and liftable above said plunger, lifting means for said plunger comprising a toggle to lift said plunger to said lower wrapping mechanism when straightened, pneumatic operating means for straightening and breaking said toggle, a lever fulcrumed on said plunger to lift said plate therefrom and pneumatically actuated means to tilt said lever to lift said plunger plate while said toggle is straight. 65
- 5 25. Apparatus of the type described which comprises, a plunger, a plunger plate supported on and liftable from said plunger, lifting means for said plunger comprising a toggle, means for lifting said plunger plate from said plunger comprising a lever fulcrumed on said plunger, pneumatic means for straightening and breaking said toggle, and pneumatic means for engaging and tilting said lever to lift said plate when 70 said plunger is held lifted by said toggle. 75
- 10 26. Apparatus of the type described which comprises, means for lifting an article and a wrapper superposed thereon and drawing said wrapper downwardly at the sides of said articles, means for tucking the sides of said wrapper sidewise beneath said article, a pair of plates mounted to swing upwardly one adjacent each end of said article, a pair of plates at each end of said article pivoted to swing from each side against the outer face of said upwardly swinging plates, and means for swinging said plates upwardly and sidewise respectively in succession from a common driving source. 80
- 15 27. Apparatus of the type described which comprises, means for supporting an article and wrapping a wrapper about its top sides and bottom surfaces, a pair of plates mounted to swing upwardly one at each end of said article to fold upwardly the projecting portions of said wrapper, plates pivoted to swing one from each side of each end of said article to fold said projecting wrapper portions inwardly, a pneumatic operating means 85 one at each end of said article for said plates, and transmission means to swing successively said upwardly and said sidewise swinging plates. 90
- 20 28. Apparatus for wrapping the projecting ends of a wrapper against the end of an article which comprises, a folding plate, a lever fulcrumed to swing said plate vertically against the end of said article, a pair of plates pivoted at the side edges of the end of said article to swing inwardly against the end of said article, a pneumatic actuating means for said plates, a spring connection between said vertically sliding plate and said actuating means to permit said actu- 95
- 25 ating means to continue movement after lift- 100 ing said plates, and a pin and slot connection between said actuating means and said side- wise swinging plates to permit movement of said actuating means before swinging said plates. 105
- 30 29. Apparatus of the type described which comprises, a plate supported to swing upwardly to a vertical plane, a pair of plates mounted to swing inwardly against the face of said plate, a pneumatic actuating means, a spring connection between said actuating means and said vertically swinging plate, links extending from said inwardly swinging plates towards said actuating means, and a pin and slot connection between said actuating means and said links. 110
- 35 30. Apparatus of the type described which comprises, a plate supported to swing upwardly to a vertical plane, a pair of plates mounted to swing inwardly against the face of said plate, a pneumatic actuating means, a spring connection from said actuating means to said upwardly swinging plate, links extending from said inwardly swinging plates and having slots at their end portions, pins moved by said actuating means and projecting into said slot and sliding therein during the movement of said vertically swinging plate, and spring acting on said links against the action of said actuating means. 115
- 40 31. Apparatus of the type described which comprises, means for wrapping a wrapper about the top sides and bottom of an article while permitting said wrapper to project beyond the ends of said article, an end folding plate, means for swinging said end folding plate into a vertical plane to fold a projecting wrapper portion upwardly against the end of said article, a pair of inwardly swinging side folding plates for folding the side projecting portions of said wrapper towards the end of said article, and means for swinging said vertical plate and said side plates in succession against the end of said article. 120
- 45 32. Apparatus of the type described which comprises, means for wrapping and holding a wrapper about the top, side and bottom surfaces of an article, a lever pivoted on a horizontal axis beyond the end of said article, a folding plate on said lever to lie in a vertical plane at the end of said article when said lever is swung upwardly, a pair of plates pivoted on vertical axes at the end corners of said article to swing inwardly to the end of said article, a pneumatic actuating means, a connection between said actuating means and said horizontally pivoted lever to permit movement of said actuating means after said lever has been swung to upper position, and a sliding connection between said actuating means and 125

said sidewise swinging plates to permit said plates to be held stationary during the early movement of said actuating means.

33. Apparatus of the type described which comprises, means for wrapping a wrapper about the top, side, and bottom surfaces of an article and for tucking in the projecting side and bottom wrapper portions against the ends of said article, a pair of guide plates above said wrapping means at the ends of said article, a pair of supports one above and carried with each of said guide plates, means for lifting said article and wrapper upwardly between said guide plates to said supports, and tucker plates slidable inwardly between said guide plates and said supports beneath the bottom of said article.

34. Apparatus of the type described which comprises, means for wrapping a wrapper about the top, side, and bottom surfaces of an article and for tucking in the projecting side and bottom wrapper portions against the ends of said article, a pair of guide plates above said wrapping means at the ends of said article, a pair of supports one above and carried with each of said guide plates, means for lifting said article and wrapper upwardly between said guide plates to said supports, plates swinging upwardly to the central portion of the bottom of said supported, wrapped article, and end tucker plates slidable between said guide plates and said supports beneath said article to said central swinging plates.

35. Apparatus of the type described which comprises, a pair of downwardly diverging guide plates having supporting lugs projecting upwardly from their upper edges, means for resiliently pressing said guide plates towards each other, means for pushing a partly wrapped article upwardly between said guide plates to rest on said supporting lugs, and end tucker plates slidable inwardly on the upper edges of said guide plates beneath said article.

36. Apparatus of the type described which comprises, a pair of downwardly diverging guide plates having supporting lugs projecting upwardly from their upper edges, means for resiliently pressing said guide plates towards each other, means for lifting a partly wrapped article upwardly between said guide plates to rest with its ends on said supporting lugs, holding plates pivoted at the sides of said supported article to swing upwardly against the central bottom portion of said article, and end tucker plates slid able on said guide plates beneath said article and notched to receive said supporting lugs.

37. Apparatus of the type described which comprises, a pair of downwardly diverging guide plates having supporting lugs projecting upwardly from the upper edges of said plates, means for resiliently pressing

said guide plates towards each other, means for lifting a partly wrapped article upwardly between said guide plates to rest with its ends on said lugs, end tucker plates slidable inwardly on the upper edges of said guide plates beneath said article, and pneumatically operated bellows for pushing said tucker plates inwardly over the edges of said guide plates.

38. Apparatus of the type described which comprises, a pair of downwardly diverging guide plates resiliently pressed towards each other and having lugs extending upwardly from their upper edges to supporting an article at its ends, a pair of tucker plates slidable on the upper edges of said guide plates inwardly beneath said article and notched to receive said lugs, and end plates above said lugs resiliently pressing against the ends of said supported article.

39. Apparatus of the type described which comprises, a pair of downwardly diverging guide plates resiliently pressed towards each other and having supporting lugs projecting upwardly from their upper edges to support an article at its ends, end tucker plates slid able over the upper edges of said guide plates to project beneath said supported article and notched to receive said supporting lugs, end holding plates above said lugs resiliently pressing against the ends of said supported article and having upward guide extensions, means for pushing a succeeding article upwardly between said guide plates and displacing said supported article upwardly to said guide extensions, and means for removing said displaced article from said guide extensions.

40. Apparatus of the type described which comprises, a pair of downwardly diverging guide plates resiliently pressed towards each other and having supports immediately above their upper edges, means for pushing a succession of articles at intervals upwardly between said guide plates to said supports and thus displacing said supported articles upwardly, a guide way above said supports to receive said displaced articles, an outlet way, and means operated at intervals to push said displaced articles sideways from said guideway to said outlet.

41. Apparatus of the type described which comprises, a pair of downwardly diverging guide plates and supports thereabove, means for pushing articles at successive intervals upwardly between said guide plates to said supports, means for tucking a wrapper beneath the bottom of said supported article, a pair of plates pivoted above said supports, a spring pressing said plates against the ends of said supported article, guides projecting upwardly from said plates to receive articles displaced upwardly from said supports, an outlet way at the level of said

guides and means for pushing an article from said guides to said outlet way at intervals.

42. Apparatus of the type described which comprises, a pair of spaced supports adapted to support an article by its lower end edges, and guide plates diverging downwardly from said supports, a pair of supports beneath said guide plates spaced to hold an article by its lower side edges, guide plates diverging downwardly from said supports, means for placing a wrapper in position beneath said lower guide plates, a plunger, a plate on said plunger, said plunger and plate being movable to a level to receive an article beneath said wrapper, means to lift said plunger and plate between said lower guide plates to the level of said lower supports, and means acting on said plunger to lift said plate therefrom to the level between said upper guide plates to the level of said upper supports.

43. Apparatus of the type described which comprises, a pair of spaced supports to support an article at its lower end edges, guide plates diverging downwardly from said supports, a pair of supports beneath said guide plates to support an article at its lower side edges, guide plates diverging downwardly from said lower supports, means for positioning a wrapper beneath said lower guide plates, a vertically movable plunger, a plate on said plunger, means for positioning and centering an article on said plunger plate beneath said wrapper, pneumatically actuated toggle means for lifting said plunger between said guide plates to said lower supports as said toggle is straightened, and pneumatically actuated means acting on said plunger to lift said plate therefrom between said upper guide plates to said upper supports.

44. Apparatus of the type described which comprises, a pair of spaced supports to support an article at its lower end edges, guide plates diverging downwardly from said supports, a pair of spaced supports beneath said guide plates to support an article at its lower side edges, guide plates diverging downwardly from said lower supports, means for positioning a wrapper beneath said lower guide plates, a vertically movable plunger, a plate supported on said plunger, means for positioning and centering an article on said plunger plate beneath said wrapper, pneumatically operated toggle means for lifting said plunger between said guide plates to said lower supports as said toggle is straightened, means for tucking said wrapper sidewise adjacent the bottom and end surfaces of said article on said lower supports, pneumatically actuated means acting on said plunger to lift said plate thereabove between said upper guide plates to said upper supports, and means for tucking said wrapper from the ends beneath said article on said upper supports.

45. Apparatus of the type described which comprises, means for guiding and supporting an article at its ends, lower means for guiding and supporting said article at its side edges, means for position a wrapper beneath said lower guiding and supporting means, means for centering an article beneath said wrapper, means for lifting said article and wrapper to said lower guide and supporting means, means for wrapping said wrapper about the bottom and sidewise over the ends of said article on said lower supports, means for lifting said partly wrapped article to said upper supports and means for tucking the end portions of said wrapper beneath said article on said upper supports.

WILLIAM C. HUGULEY.
